CONTROL AND SAFETY SYSTEM FOR
STRAND WORKING APPARATUS

Einer W. Larsen, Chicago, Ill., assignor to Western Electric Company, Incorporated, New York, N. Y., a corporation of New York

Application May 16, 1930, Serial No. 453,004

22 Claims. (Cl. 205—16)

This invention relates to a control and safety system for strand working apparatus, particularly for use with wire drawing machines.

The principal object of the invention is to coordinate a strand slackener of a strand working apparatus with the take-up means and incidentally to provide an interlocking system for positively safeguarding and controlling the operating parts of a strand working apparatus.

10 In accordance with this and other objects, one embodiment of the invention contemplates the provision of an automatic device for slackening the wire in a wire drawing machine at the moment the take-up reel stops rotating, (the capstan driving power not being shut off before this moment), a system which is incidentally electrically interlocked so that the take-up mechanism can be operated only when the doors to the supply, wire drawing capstan and take-up compartments 15 are closed and the reel is locked on its arbor.

Automatic devices are also provided for positively stopping the wire drawing and take-up units after the reel is full, the wire breaks, the end of the wire pulls through the machine, the reel becomes loose on its arbor or if the doors to the supply compartment are opened. Remote control switches are provided to electrically control mechanical and pneumatically operated devices for effecting the actuation of the doors to the 25 wire drawing capstan and take-up compartments, the motor controls, and to control valves for the wire drawing lubricating compound, pneumatic brake, the wire slackening mechanism and a baffle mechanism.

30 The features and advantages of the invention will be better understood from the following detailed description and one embodiment thereof taken in conjunction with the accompanying drawings, wherein

40 Fig. 1 is a front elevational view of a high speed wire drawing machine constituting an embodiment of the invention, and showing the arrangement of the compartment;

45 Fig. 2 is a sectional view taken substantially along the line 2—2 of Fig. 1;

Fig. 3 is a detailed sectional view of the take-up compartment door construction;

Fig. 4 is an enlarged front elevational view of the slackening mechanism;

50 Fig. 5 is a sectional view taken along the line 5—5 of Fig. 4, and

55 Fig. 6 is a wiring diagram showing the automatic electrical controlling means in connection with a schematic illustration of the various operating parts effected by a closing of the circuits.

Referring now to the drawings in which similar elements are designated by identical reference numerals, the wire drawing apparatus, indicated generally at 10, consists of a supply compartment 11 (Fig. 1), for handling rod stock 12, 5 a drawing compartment 13 wherein the rod stock is reduced to wire 15, and a take-up compartment 16 mounted upon a common foundation or base 17. The supply compartment 11 consists of a portable platform 18 having wheels 19 mounted upon the under surface thereof and a pair of truncated cone shaped posts 21 mounted upon the upper surface thereof. Suspended from a roof of the supply compartment are brackets 22 arranged to support idler pulleys 23 for receiving 15 the rod stock 12 from the posts 21. The supply compartment 11 is provided with an open end 24 having a door 25 which may be of any desired construction preferably of a roll type as shown in Fig. 1.

The drawing compartment 13 contains a housing 26 (Fig. 2) which has reduced portions 27 and 28 at the top and bottom thereof designed to cooperate with the top and bottom walls of the compartment to form door receiving chambers 29 and 32. Stepped capstans 33 and 34 are rotatably mounted upon the front wall 35 of the housing 26, the capstan 33 receiving the rod stock 12 after passing from the pulley 23 and through a die in a die block 36. A plurality of 30 idler sheaves 37 are rotatably mounted upon an eccentric shaft 38 (Figs. 2 and 4), and are positioned above the capstan 33, while a plurality of idler sheaves 39 are rotatably mounted upon an eccentric shaft 42 and positioned above a capstan 34. The rod stock 12 is wound around the capstan 33 and the idler sheaves 37 as shown in Fig. 2 and as the material or rod stock passes from the idler sheaves 37 it is drawn through dies in a die block 43. After the wire has been drawn through the dies in the die block 43, it passes around the last and largest circular grooved step of the capstan 33 and over an idler pulley 44. The wire 15 passing from the idler pulley 44 45 passes over the innermost idler sheave 39 and is then wound around the capstan 34 and the other idler sheaves 39 in the same manner as the wire is wound around the capstan 33 and the idler sheaves 37 (Fig. 2). A die block 45 is disposed 50 between the idler sheaves 39 and the capstan 34 for supporting dies (not shown) arranged to receive the wire 15 as each convolution thereof passes from the idler pulleys 39 to the capstan 34. The wire 15, after being drawn through the 55

dies (not shown), is passed under an idler pulley 46, over a control idler pulley 47 and onto the take-up reel 48, the latter being fixedly mounted upon a driven shaft 49 which is rotated by a take-up motor hereinafter described.

The slackening mechanism shown in Figs. 4 and 5 provides adjustable supports for the idler sheaves 37 and 39. The shafts 38 and 42 of this mechanism are rotatably mounted in bearing members 52 so that they extend outwardly and upwardly. The inner ends of the shafts 38 and 42 have gears 53 rigidly mounted thereupon and in mesh with piston-actuated rack members 54, the inner reduced portions 55 thereof extending through packing units 56 in end walls of a cylinder 57 and fixed to a piston 58 in the cylinder. Fluid or air lines 59 and 60 communicate with each end of the cylinder 57 for a purpose hereinafter described.

20 The wire drawing compartment has an aperture 62 which is arranged to be closed by swinging doors 63 and 64, having supporting arms 65 and 66 keyed to pivot shafts 67 and 68, respectively. The shafts 67 and 68 are rotatably mounted in the walls of the housing 26 or in any suitable support, and have gears 70 and 71 mounted thereupon and in mesh with rack portions 72 and 73, respectively, of an actuating yoke 74. The yoke 74 is slidably mounted upon a horizontal beam 75 and has a toothed portion 76, the teeth of which mesh with a gear 77 keyed to a stub shaft 78. The stub shaft 78 is rotatably mounted in any suitable bearing (not shown) and has a lever 79 mounted upon one end thereof, the outer end of which is pivotally secured to a connecting or piston rod 80. The piston rod 80 extends through an aperture in a cover 81 of a cylinder 82, and is fixed to a piston 83 which is movably disposed in the cylinder. A 40 pivotal mounting indicated at 84 is provided for the cylinder so as to allow for a swinging movement due to the lever connection.

The take-up compartment 16 containing, as has already been described, the idler pulleys 46 and 47, the take-up reel 48 and the shaft 49, has a door 85 to close an aperture 86 thereof. The general construction of this door 85 is shown in Fig. 3 wherein a plurality of horizontally disposed door sections 87 have their ends fixed to lengths 88 of chains which ride over idler sprockets 89 and driven sprockets 92, and have their inner ends secured to brackets 93, fixed to the rear wall of the take-up compartment. Counter-weights 94 are connected to the brackets 93 by 55 means of pivotal links 95 and to the chains by means of links 96 and clamping members 97. The driven sprockets 92 are rigidly mounted upon the ends of a shaft 98 which has fixedly mounted thereupon a relatively small gear 99 in mesh with a relatively large gear 101 which is fixedly mounted upon a stub shaft 102. A pinion 103 is fixedly mounted upon the stub shaft 102 and is in mesh with a rack portion 104 of a piston rod 105, the opposite end of which is secured to a piston 106 slidably disposed in a cylinder 107.

The operation of the apparatus is controlled by the arrangement of circuits shown in Fig. 6 which are so related that the device will be automatically controlled and will not operate until the apparatus is in readiness and the doors of the various compartments are closed. The door 25 to the supply compartment may be closed manually, or by any suitable means, and in so 75 doing switches 108 are closed. By closing

switches 109 and 110 a magnetic switch 112, the holding coil of which is in series with a time switch 113, is closed, thus energizing a solenoid 114 for actuating valves 115, 116, and 117. By opening the valve 116, air under pressure is allowed to pass from the supply pipe 118 through the valve 116, an air line 119 to the cylinder 107, thus moving the piston 106 downwardly (Fig. 6) and actuating the rack 104, the pinion 103, the gears 101 and 99, rotating the shaft 98 and in turn moving the chains by their engagement with the sprockets 92 so as to move the door 85 into closed position.

The air in the cylinder 107, beneath the piston 106 is exhausted through an air line 120, the valve 116 and an exhaust port 121. By actuating the valve 117 the air under pressure from the supply line 118 is allowed to pass through the air line 123 and into the cylinder 82 (Figs. 2 and 6) thus moving the piston 83 downwardly, and 20 actuating the lever 79 so as to move the actuating yoke 74 outwardly and cause the doors 63 and 64 to be moved into closed position adjacent the aperture 62. Flap valves 125 and 126 are disposed in the air lines 123 and 125 respectively, 25 and have relatively small apertures therein to allow a slow passage of air into the cylinders 82 and 126, respectively, thus causing a slow closing of the doors 63 and 64 and a slow movement of the valve 129 and the valve 135. The air 30 from beneath the piston 83 is exhausted through an air line 124 through the valve 117 and an exhaust port 119. The actuation of the valve 117 also allows air under pressure to pass through an air line 125 to a cylinder 126 so as to force 35 a piston 127 downwardly with a valve rod 128 which is carried thereby so as to move a valve 129 into engagement with a valve seat 130 of a compound drain aperture. The valve rod 128 is provided with a toothed portion 133 in mesh 40 with a gear 134 of a compound supply valve 135, thus moving the valve into open position so as to allow compound for the dies to pass from a supply pipe 136 through the valve 135 and through a supply pipe 137 to the dies in the 45 die blocks 43 and 45. Although only one unit is shown for closing the compound drain and opening the valve for admitting compound to the dies, any number of units may be employed depending upon the number of die blocks in the 50 apparatus. The air in the cylinder 126 beneath the piston 127 is exhausted through an air line 138, the air line 124, the valve 117 and the exhaust port 125.

The wire 15 in passing over the control idler 55 pulley 47 (Figs. 1 and 6) moves a lever 140 about its pivot 141 and against the tension of a spring 142 so as to close the switch 143 and allow a valve 144 to be closed by a spring 145. Therefore, by the actuation of the valve 115 the air 60 line 146 is in communication with the air supply line 118 through the valve 115 so as to direct air under pressure past the valve 144 and through an air line 147 to a cylinder 148 to actuate a piston 149 and in turn actuate a baffle mechanism 65 152 when the valve 144 is open due to the breaking of the wire 15 or the removal of the wire from the control idler pulley 47 when the entire supply of wire is drawn therefrom. The baffle mechanism consists of a roller supporting member 153 which is pivotally mounted at 154 and normally held out of engagement with the wire wound upon the take-up reel 48 by a spring 155, but arranged to be actuated by the actuation of the piston 149 so as to move rollers 156, carried 70 75

thereby, into engagement with the wire on the take-up reel so as to prevent the wire thereupon from loosening.

After the door 85 to the take-up compartment has been closed, an opening 157 therein will be moved into general alignment with a telltale switch 158 so that the operator may reach through the opening and close the switch. The telltale switch 158 may be operated by any counter commonly used for controlling electrical contacts, but the preferred type of counter is disclosed in Larsen Patent No. 1,904,869, April 18, 1933. By closing the switch 158, a switch 160 is closed due to the energizing of a solenoid 161, starting the take-up motor 162. The switch 160 simultaneously energizes a solenoid 163 so as to actuate the valve 164 to permit air under pressure to pass from the supply line 118 through the valve 164, the air line 60 and into the cylinder 57, thus moving the piston 58 from the position shown in Fig. 6 toward the position shown in Fig. 4, thus actuating the eccentric shafts 42 through the rack and gear connection so as to move the idler sheaves 37 and 39 upwardly from their respective capstans 33 and 34. The actuation of the valve 164 also allows air under pressure to pass from a cylinder 165 of a take-up brake, indicated generally at 166, so as to allow the tension of springs 168 to move the fixed brake member 170 from engagement with a rotatable brake member 171 of the shaft 49 (Figs. 1 and 6).

The starting of the take-up motor 162 also energizes the time switch 113 which is kept closed for a set interval to keep the switch 112 closed 35 until after a pressure controlled switch 173 has closed. The closing of the pressure controlled switch 173 is effected, shortly after the take-up motor is started, by means of an oil pump 174 which is actuated by the motor 162 and operatively connected to the pressure controlled switch 173.

When the take-up spool or reel 48 becomes full, the telltale mechanism automatically breaks the circuit to the take-up motor 162 and de-energizes 45 the solenoid 163, thus allowing the valve 164 to be moved into the opposite position by a weight 175. The take-up brake mechanism 166 is actuated immediately upon the movement of the valve 164 by the weight 175, due to the air under pressure passing from the supply line 118 through the valve, air lines 176 and 177, to the cylinder 165. When the motor 162 comes to rest, the pressure controlled switch 173 opens, thereby de-energizing the solenoid 114 allowing a weight 180 to 50 move the valve 115 to permit air under pressure to pass from the supply line 118, through a flap valve 181 and through the air line 59 to the cylinder, thus actuating the slackening mechanism to loosen the wire. Therefore, the slackening mechanism and the take-up mechanism work in perfect coordination so as to prevent burning and breaking of the wire which would occur due to the slipping of the wire upon the capstans if the wire were held taut. An indicating light 182 is 55 illuminated only while the pressure controlled switch 173 is closed and by this means the operator can know when the motor 162 has stopped, the pressure controlled switch broken, and the slackening mechanism actuated.

An actuating rod 183, which supports the weight 180 and is actuated by the solenoid 114 has lugs 184 adapted to actuate the valves 116 and 117 upon the upward movement thereof, but is moved free of the valves 116 and 117 downwardly.

In order to open the doors 63 and 64 to the drawing compartment 13, a switch 187 is closed, thus energizing the solenoid 188 so as to actuate the valve 117, allowing air under pressure to pass from the supply line 118 through the air line 124 to the cylinder 82, forcing the piston 83 to the upper position (Fig. 6), and actuating the yoke 74, due to the operative connection with the piston, thus swinging the doors 63 and 64 about their pivots into open positions. A simultaneous actuation of the piston 127, with the actuation of the piston 83, is brought about by the air under pressure entering the cylinder 126 through the air line 138, thus closing the valve 135 so as to shut off the supply of compound to the dies and to move the valve 129 away from the drain 130. The take-up compartment door 85 is opened by first closing the switch 190 so as to energize the solenoid 191 and move the valve 116 to allow air under pressure to pass from the air supply line 118 therethrough, through an air line 120 into the cylinder 107, thus moving the piston 106 upwardly, causing an actuation of the gears and sprockets which are operatively connected to the rack 104 to move the door 85 into 25 open position while aided by the counterweight 94. The door 25 to the supply compartment may be opened in a similar manner if a similar means is employed therefor, or it may be opened manually by the aid of a handle 192.

30

What is claimed is:

1. In a strand working apparatus, means for advancing a strand, means for taking up the strand as advanced, means for tightening the strand while advancing, means for stopping said 35 take-up means, and means responsive to the stopping of said take-up means for rendering said tightening means ineffective.

2. In a strand working apparatus, a capstan for receiving and advancing convolutions of 40 strand material, a sheave for receiving the convolutions of material from said capstan, means for varying the relative positions of said capstan and said sheave for changing the tension of the strand material while advancing, a takeup 45 means for receiving the strand from said sheave, means for stopping said take-up means, and means responsive to said stopping means for operating said varying means to relieve the tension.

3. In a strand working apparatus, means for working a strand, means for advancing the strand through said working means, means for stopping the actuation of said advancing means, means for varying the tension of said strand, means for 55 actuating said varying means for tightening the tension of the strand while advancing, and means rendered effective responsive to the stopping of said advancing means for actuating said varying means for relieving the tension of the strand. 60

4. In a wire drawing machine, a compartment containing supply means, a compartment containing dies and a capstan for drawing wire through said dies, a compartment containing a take-up mechanism for the drawn wire, doors for 65 each of said compartments, electric power means for operating said take-up mechanism, a circuit for supplying current to said power means, means for opening and closing said circuit, said last mentioned means being so arranged that said 70 circuit cannot be completely closed until all of said doors are closed, means responsive to a breakage of said wire and to said wire becoming loose for stopping said power means, means responsive to the opening of one of said doors for 75

- stopping said power means, means to prevent opening of the other two doors while said take-up means is operating, and means responsive to stopping said take-up means for rendering said 5 capstan inoperative to advance the wire.
5. In a wire drawing machine, a compartment containing supply means, a compartment containing dies and a capstan for drawing wire through said dies, a compartment containing a 10 take-up mechanism for the drawn wire, doors for each of said compartments, electric power means for operating said take-up mechanism, a circuit for supplying current to said power means, means for opening and closing said circuit, said 15 last mentioned means being so arranged that said circuit cannot be completely closed until all of said doors are closed, means responsive to a breakage of said wire and to said wire becoming loose for stopping said power means, means responsive to the opening of one of said doors for 20 stopping said power means, and means to prevent opening of the other two doors while said take-up means is operating.
6. In a wire drawing machine, a compartment containing supply means, a compartment containing dies and a capstan for drawing wire through said dies, a compartment containing a take-up mechanism for the drawn wire, doors for each of said compartments, electric power means 25 for operating said take-up mechanism, a circuit for supplying current to said power means, means for opening and closing said circuit, said last mentioned means being so arranged that said circuit cannot be completely closed until all of said doors are closed, means responsive to a breakage of said wire and to said wire becoming loose for stopping said power means, and means responsive to the opening of one of said doors for 30 stopping said power means.
7. In a wire drawing machine, a compartment containing supply means, a compartment containing dies and a capstan for drawing wire through said dies, a compartment containing a take-up mechanism for the drawn wire, doors for each of said compartments, electric power means 35 for operating said take-up mechanism, a circuit for supplying current to said power means, and means for opening and closing said circuit, said last mentioned means being so arranged that said circuit cannot be completely closed until all of said doors are closed.
8. In apparatus of the character described the combination of means for working strand material including a rotatable member over which a 40 strand passes, means for spooling the strand delivered by the working means, control means for automatically stopping the spooling means when the spool becomes full, means supporting said rotatable member so as to permit movement thereof transversely of its axis for slackening said strand, actuating means for moving said supporting means, and means associated with said control means for controlling said actuating means whereby the latter is automatically operated to slacken said strand upon the stopping of said spool.
9. In apparatus of the character described the combination of means for working a strand of material including an idler sheave over which a 45 strand passes, eccentric mounting means for said sheave, means for spooling the strand delivered by said working means, actuating means for rotating said eccentric mounting means to thereby slacken said strand, and means responsive to the operation of said spooling means for 50 controlling the supply of motive power to said actuating means.
10. In apparatus of the character described the combination of a casing, means in said casing for working a strand of material including a rotatable member over which said strand passes, winding means for taking up the strand delivered by said working means, a control for said winding means, a shaft supported by said casing and having an eccentric spindle portion upon which 55 said rotatable member is mounted, means for automatically rotating said shaft to thereby slacken said strand upon the stopping of the winding means and control means actuated upon the stopping of said winding means for rendering the shaft rotating means effective.
11. In apparatus of the character described the combination of means for working a strand of material, means associated with said working means for slackening said strand, winding means for taking up the strand delivered by said working means, and means under the control of said winding means for stopping said winding means and actuating said slackening means substantially simultaneously with the stopping of the winding 20 means.
12. In apparatus of the character described the combination of means for working a strand of material, winding means for taking up the strand delivered by said working means, means under the control of said winding means for stopping said winding means, means for slackening said strand, and control means responsive to the stopping of said winding means for rendering said slackening means effective.
13. In apparatus of the character described the combination of means for working a strand of material, winding means for taking up the strand delivered by said working means, and means responsive to the stopping of said winding means for slackening said strand substantially simultaneously with the stopping of said winding means.
14. In apparatus of the character described the combination of means for working a strand of material including a rotatable member over which 40 said strand passes, movable mounting means for said rotatable member, means for spooling the strand delivered by said working means, actuating means for moving said mounting means to thereby slacken said strand, and means under the control of said spooling means for rendering said actuating means effective.
15. In apparatus of the character described the combination of means for working a strand of material including a rotatable drum and a rotatable 45 idler sheave over which said strand passes, mounting means for said rotatable sheave, said mounting means being movable to vary the distance between the axis of said sheave and the axis of said drum, means for spooling the strand delivered by said working means, actuating means for moving said mounting means to decrease said distance to thereby slacken said strand, control means for said actuating means including an electro-magnetic device, and means under the 50 control of said spooling means for de-energizing said device substantially simultaneously with the stopping of said spooling means.
16. In apparatus of the character described the combination of means for working a strand of material including a rotatable drum and an idler sheave over which the strand passes, a spindle upon which said sheave is rotatable, movable mounting means for said spindle whereby the spacing of the axis of said spindle from the axis 55

or said drum may be varied to thereby slacken said strand, a rotatable spool for winding the strand delivered by the working means, means for rotating said spool, actuating means for said movable spindle mounting means, and control means for said actuating means, said control means being responsive to the stopping of said driving means for rendering said actuating means effective for slackening said strand.

17. In apparatus of the character described the combination of means for working a strand of material including a rotatable drum and an idler sheave over which the strand passes, a spindle upon which said sheave is rotatable, movable mounting means for said spindle whereby the spacing of the axis of said spindle from the axis of said drum may be varied to thereby slacken said strand, a rotatable spool for winding the strand delivered by the working means, driving means for rotating said spool, actuating means for said movable spindle mounting means including a fluid pressure responsive device operatively connected to said mounting means, a valve for controlling the supply of motive fluid to said pressure responsive device, actuating means for said valve including an electro-magnetic device, and speed responsive switch means for controlling the energization of said electro-magnetic device whereby said fluid pressure responsive device is rendered operative 20 for slackening said strand upon the stopping of said driving means.

18. In apparatus of the character described, the combination of means for working a strand of material, winding means for taking up the strand delivered by said working means, and means for slackening the strand substantially simultaneously with the stopping of said winding means, said slackening means including an electromagnetic device and means responsive to the stopping of said winding means for deenergizing said device substantially simultaneously with the stopping of said winding means.

19. In apparatus of the character described, the combination of means for working a strand of material including a rotatable drum and an idler sheave over which said strand passes, means for taking up the strand delivered by said working means, and means responsive to the stopping of

said winding means for slackening the strand substantially simultaneously with the stopping of said winding means, said slackening means including an eccentrically mounted spindle supporting said idler sheave and fluid pressure responsive means for rotating said spindle.

20. In apparatus of the character described, the combination of means for working a strand of material including a rotatable drum and an idler sheave over which said strand passes, means for taking up the strand delivered by said working means, means responsive to the stopping of said winding means for slackening the strand substantially simultaneously with the stopping of said winding means, said slackening means including an eccentrically mounted spindle supporting said idler sheave, fluid pressure responsive means for rotating said spindle, valve means for controlling said fluid pressure responsive means, and electro-magnetic means for controlling said valve means.

21. In apparatus of the character described, the combination of a rotatable spool carrier, driving means for rotating said carrier for winding material upon a spool, holding means mounted for movement relative to said spool, means under the control of the material being wound for pressing said holding means against the wound material, and means rendered effective substantially simultaneously with the stopping of the spool carrier for withdrawing said holding means.

22. In apparatus of the character described, the combination of a rotatable spool carrier, driving means for rotating said carrier for winding material upon a spool, holding means mounted for movement relative to said spool, spring means normally biasing said holding means away from said spool, fluid pressure responsive means for pressing said holding means against the wound material, valve means under the control of the material being wound for supplying fluid pressure to said fluid pressure responsive means and responsive to the stopping of the spool carrier for interrupting the supply of fluid pressure to said fluid pressure responsive means and thereby rendering said spring means effective for withdrawing said holding means.

EINER W. LARSEN.
